UNITED STATES PATENT OFFICE

BENJAMIN F. PERKINS, OF HOLYOKE, MASSACHUSETTS, ASSIGNOR TO AMERICAN TISSUE MILLS, OF HOLYOKE, MASSACHUSETTS, A CORPORATION OF MASSACHUSETTS

METHOD OF MAKING ARTICLES OF PAPER

Application filed October 1, 1931. Serial No. 566,196.

This invention relates to improvements in methods for making articles from paper to simulate fabric.

The principal objects of the invention are 5 directed to the improvements in methods for making paper articles to simulate similar articles of fabric.

Various novel features and advantages of the invention will be hereinafter more fully 10 referred to in connection with the accompanying description of the preferred form of the invention which for purposes of disclosure is illustrated in the accompanying drawing wherein:

15 Fig. 1 is a diagrammatic plan view of a pair of rolls with webs passing therebetween in accordance with the novel method of the invention.

Fig. 2 is a diagrammatic elevational view 20 to explain the novel features of the invention.

Fig. 3 is an enlarged fragmentary sectional view through the end portions of coating rolls such as are used to practice the invention, and

25 Fig. 4 is a partial sectional view through an article made in accordance with the invention to explain certain novel features thereof.

Referring now to the drawing more in detail the invention will be fully described.

30 According to the novel features of this invention in its broad aspect I provide a method for making articles such as napkins, handkerchiefs and the like from paper so that they simulate similar articles made from fabric.

35 According to certain features of the invention the paper material is acted upon in such a way that the finished product has all the desirable qualities of fabric in that it is soft, pliable and fluffy.

40 In carrying out the invention I superpose plies or webs of crepe paper and this may be done by leading a web or webs W of crepe paper from rolls 3 thereof and passing the same between coating pressure rolls 2.

45 I preferably use crepe paper because since

it is creped it is more or less pliable and flexible. In this way the paper lends itself to the treatment or action of the rolls.

The rolls 2 and 2 are preferably provided with alternate ridges and grooves which may 50 be done by engraving, etching or by any suitable means. The alternate grooves and ridges are arranged to extend circumferentially of the roll as well as longitudinally thereof, and are so arranged as to simulate 55 the interwoven elements of a fabric such as for instance the warp and weft elements of woven linen or the like.

The rolls 2 are so set that the superposed webs W passing therethrough are pressed 60 together so that they adhere or stick together and form a laminated web. It is preferable that the webs be joined substantially throughout their area so that one web is not movable relative to the other and in this way 65 a composite web is provided which on opposite sides has the appearance of fabric, linen or whatever effect may be carried by the surfaces of the rolls.

As a further feature there are provided in 70 the surfaces of the rolls grooves 8 which may extend circumferentially as well as longitudinally thereof. As the webs pass between the rolls they are relieved of pressure along these grooves so that as at R in Fig. 4 the 75 webs are more or less separated to provide a raised border along the marginal edges of the combined webs.

The superposed joined together webs indicated by S may be cut along lines indicated 80 at 9 to provide separate articles such as napkins, handkerchiefs, and the like. The rolls may be provided with co-operating cutting devices for severing the webs or it may be separated in any other convenient manner. 85

By employing crepe paper, as has been explained, the webs before they are joined together are of course flexible and extremely pliable so that during the pressing and marking step the webs may readily receive the 90

markings from the rolls. The indentations of the creped web are caused to interlock so that the webs are secured together to form the composite web.

5 By thus employing the relatively soft, fluffy and readily pliable crepe paper and then finishing the surfaces thereof with a design to simulate a fabric, the composite web is not only pliable and fluffy and has the soft 10 feel of fabric, but it has the appearance thereof as well.

It has been possible to produce composite webs after the manner of the invention which not only simulate in every respect a web of 15 fabric, but when cut to proper size and shape there have been provided handkerchiefs, napkins, and the like of paper which are equal to those of fabric in that they are soft, fluffy and pliable. In fact, in some cases, they are 20 superior to handkerchiefs and napkins made from many kinds of fabric, while the cost thereof is of course much less.

Having described the invention in the form at present preferred, what I desire to claim 25 and secure by Letters Patent of the United States is:

1. The method of producing handkerchiefs and the like from paper to simulate woven linen which consists in, subjecting superposed 30 webs of crepe paper to the action of coacting pressure rolls which have the surfaces thereof provided with alternate grooves and ridges arranged to simulate woven linen and being provided with grooves so as to press the webs 35 together outside said grooves to form a united composite web with substantial areas thereof joined together and having separated portions at spaced intervals.

2. The method of producing handkerchiefs and the like from paper to simulate woven fabric which consists in, subjecting superposed webs of paper to the action of coacting pressure rolls which have the surfaces thereof provided with alternate grooves and ridges 45 simulating woven fabric and being provided with co-operating spaced grooves so as to press the webs together outside said grooves to form a united composite web with substantial areas thereof joined together and simulating woven fabric and having separated portions at spaced intervals.

3. The method of producing handkerchiefs and the like from crepe paper to simulate woven fabric which consists in, superposing 55 plies of crepe paper and subjecting them to the action of pressure rolls, the said rolls having marking surfaces provided with alternate grooves and ridges to simulate woven fabric and coacting spaced grooves arranged circumferentially and longitudinally of said rolls, whereby the plies are pressed and joined together by said rolls throughout the substantial area thereof by the marking surfaces of the rolls to simulate fabric and have separated portions formed by the grooves in said 65

rolls which surround the said substantial areas.

4. A paper handkerchief or the like comprising in combination, layers of crepe paper in superposed relation impressed with interlocked alternate grooves and ridges simulating woven fabric holding the layers together throughout a substantial area of the layers which area is surrounded by separated portions of the layers adjacent the marginal edges of the handkerchief.

In testimony whereof I affix my signature.

BENJAMIN F. PERKINS.
